UNITED STATES PATENT OFFICE

BERT A. SMITH, OF FAYETTE, IOWA

END GATE AND RETAINING MEANS THEREFOR

Application filed April 30, 1929. Serial No. 359,284.

This invention relates to an improved end gate construction, and complementary retaining means for securely holding the gate in closed position.

5 Briefly stated, the wagon body has its side walls equipped on the interior surfaces with vertical and longitudinally spaced strips defining therebetween keeper seats in which the end portions of the end gate are received.

10 The end gate is provided on its exterior side with vertical end cleats and associated with these cleats and the side walls of the wagon body is a novel mechanical retaining structure which constitutes the principal novelty 15 of the present invention.

In carrying the invention into actual practice, I have evolved and produced what I believe to be a simplified and dependable structure carried by the end gate and cooperable 20 with the side walls of the vehicle body in a manner to securely hold the gate in closed position.

The respective details and their particular relative association will become more readily 25 apparent with the following description and drawings.

In the drawings:

Figure 1 is a rear elevational view of the wagon body and end gate constructed in accordance with the invention showing the retaining device in locking position.

Figure 2 is a top plan view of the structure seen in Figure 1.

Figure 3 is a detail view of the contractible and expansible take-up device.

Figure 4 is a transverse vertical section on an enlarged scale taken approximately upon the plane of the line 4-4 of Figure 1.

Figure 5 is a fragmentary detail sectional and plan view showing certain of the details.

Figure 6 is an outside elevational view of the structure seen in Figure 5.

As seen in Figures 1 and 2, the reference character 8 designates generally the wagon body which includes the customary side walls 9. As before indicated, these are provided on their inner sides with vertical side strips 10, spaced apart to provide keeper seats for removable reception of the end portions of the end gate 11. The end gate is provided ad-

jacent the opposite ends and on its rear side with vertical cleats 12.

As seen in Figure 6, the reference character 13 designates a metallic wear disc having a vertical slot 14 formed therein. This slot 55 registers with similar slots formed in the parts 9 and 10. Also as seen in Figure 5, the disc 13 has a depression intersecting the slot and providing a seat for reception of the longitudinally adjustable binding and retaining 60 means. This means is of a mechanical nature and is manually manipulated and is characterized principally by three distinguishable parts. For instance, as seen in Figure 1, I provide a centrally disposed take-up device, generally designated by the reference character 15 and this is cooperable at its opposite ends with a pair of oscillatory and 65 slidably mounted rods 16. Each rod 16 extends through openings in the adjacent cleat 12, guide strip 10 and side wall of the wagon body. The rod is provided on its outer end with a T-head 17, which is cooperable with the disc 13. When in locking position, the head intersects the slot and is received in the depressed seat, as seen in Figure 5. When 70 in releasing position, the head is turned away to align with the slot 14 to permit it to be retracted through the opening in the complementary side wall 9, and the opening in the guide 10, when it is drawn into the space 18 as 75 shown in dotted lines in Figure 1.

This rod is provided inwardly of the cleat 12 with a combined weight and handle 19. 80 Obviously, when the handle 19 is swung down to the position seen in full lines in Figure 1, at the left, the cross head 17 intersects the slot 14. When, however, the handle is swung up at right angles to the end gate as seen in dotted lines in this figure, the head 17 is in a position to permit it to be drawn through and into the space 18 for releasing the end gate. Each rod 16 is provided adjacent its inner end with a stop collar or washer 20 held in place by a cotter key. This 85 end portion cooperates with the take up device 15. The take up device is mounted on an appropriate bracket 21.

The description of the take up device 15 is reserved for this point to call attention 100

to the fact that the take up device may be of variable construction.

For instance, as seen in the structure represented in Figures 1 and 2, the take up device comprises links 22, and 23, having their outer ends directed upwardly as at 24 and apertured for passage of the adjacent end portions of the complementary rods 16. Each link 22 passes through the outstanding flange of the attaching bracket 21, as seen in Figure 1. The adjacent ends of these two links are connected with operating lever 24. This lever has the handle portion terminating in a downwardly directed extremity 25. The opposite end portion is of forked construction as represented at 26.

The forked arms are connected with the adjacent ends of the links as seen in Figure 3. The reference character 27 designates a retaining loop, which is slidable on the link 23 and cooperable with the adjacent end portion of the lever 24. This functions as a retaining element.

With this arrangement it is obvious that when the lever 24 is in the position seen in Figure 1, the adjacent end portions of the links 22 and 23 are drawn into overlapping relation, thus disposing the take-up device in contracted position. In this position, the loop 27 is slipped over the end portion of the lever to hold the lever in place. The operating connection between the links 22 and 23 with the rods 16 obviously serves to draw the rods toward each other and to bind the T-heads 17 against the respective discs 13. This, therefore produces the desired locking action and maintains the end gate securely in closing position.

When it is desired to remove the end board, the loop 27 is slipped off of the lever. Then the lever is swung downwardly. This extends the links 22 and 23 and allows freedom of movement of the respective rods 16. Then, the operator takes hold of the handle 19 and rocks or oscillates the respective shaft 16 upwardly. Then each shaft is pulled inwardly so that it assumes the dotted line position seen in Figure 1. It is then in releasing position and the end board may be slipped out of the keeper seats.

This structural arrangement facilitates placement and maintenance of the end gate.

By carefully considering the description in conjunction with the drawings, a clear understanding of the construction and operation of the invention will be had. Therefore a more lengthy description is regarded unnecessary.

Minor changes in the shape, size and arrangement of details coming within the field of invention claimed may be resorted to, in actual practice, if desired.

I claim:

In a structure of the class described, in combination, an end gate provided adjacent

its opposite ends with vertical cleats having horizontal holes formed therein, clamping rods slidable and rotatable in said holes, the rods being provided at their outer ends with T-heads and adjacent their inner ends with stop collars, a handle mounted on the intermediate portion of each rod, a bracket on the intermediate portion of the end gate, a link slidably mounted on said bracket, a lever pivotally connected to said link, a second link pivotally connected to said lever, retaining means cooperable with the lever and the last named link, the outer end portions of said links being directed laterally and formed with openings for passage of the collar equipped ends of said rods.

In testimony whereof I affix my signature.
BERT A. SMITH.
